KNITTING APPARATUS

Robert Grant, Baltimore, Md., assignor to Western Electric Company, Incorporated, New York, N. Y., a corporation of New York

Application May 28, 1938, Serial No. 210,679

3 Claims. (Cl. 66—9)

This invention relates to knitting apparatus and more particularly to apparatus for actuating knitting needles.

In the manufacture of certain types of knitted coverings, for instance, a knitted covering for an electrical conductor, it has been found desirable to actuate the knitting needles by means of levers operating on a cam. However, the use of levers operating directly on a cam causes wear of the lever arms due to the reciprocating and lateral motion between the lever arms and the cam.

An object of the present invention is to provide an apparatus for actuating the knitting needles which will be practically frictionless and simple and rugged in construction.

One embodiment of the invention contemplates a knitting machine having a hollow rotatable carrier or needle cylinder supporting a plurality of needles about a core passing therethrough, and cam means in combination with a plurality of levers rotatable with the needles, one arm of each lever being connected to a needle, the other arm of each lever having a ball in rolling contact with the cam, and adjustable together with the needles in respect to the cam.

Other objects and features of the invention will appear from the following detailed description of one embodiment thereof taken in connection with the accompanying drawing, in which the same reference numerals are applied to identical parts in the several figures and in which,

Fig. 1 is a front elevation partly in section of a knitting machine constructed in accordance with the invention; and

Fig. 2 is a detail of the needle-actuating lever and cam.

The embodiment herein disclosed comprises a circular knitting machine of the same general type as disclosed in the copending application of B. K. Ford, Ser. No. 104,774, filed October 9, 1936, now Patent No. 2,126,250. Only enough is disclosed herein to enable a clear understanding of the invention.

The machine has a stationary frame 20 supported by means not shown. Journaled in the frame is a hollow shaft 21 rotated by gears 22 and 23, which are driven by means not shown. Within the upper end of shaft 21 is secured a hollow extension or needle bed 25.

Formed in the outer surface of the needle bed are a plurality of vertical radial slots 28 and in each of the slots a knitting needle 29 of conventional type is reciprocably movable. On the upper portion of the needle bed an annular member 33 formed with a horizontal flange 133 is ad-

justably secured. The member 33 has a projection 233 extending into one of slots 28 to key the member 33 against rotation on needle cylinder 25, but enabling member 33 to be adjusted vertically on the cylinder.

Under flange 133 and near its outer periphery are mounted a plurality of studs 37. On the lower end of each stud is pivoted a bell crank lever 38, whose horizontal radially inwardly extending arm enters, at the tip thereof, the corresponding slot 28 and by means of a notch in the tip of the lever arm engages a corresponding needle. The other arm extends downwardly toward the base of the machine.

15 The lower end of the downwardly extending arm is formed into a cylindrical extension 2.

Below the flange 133 and stationarily secured on top of frame 20 is a pair of complementary cam members 39 and 40 whose opposed edges define between them an endless cam slot 41. The cross-section of this cam slot forms two opposing arcs of a circle.

20 Held in the cam groove so that they may roll freely but cannot escape are a plurality of ball bearings 3. Each bearing has a circular bore 4 drilled through its center. The cylindrical extension 2 on the end of each downwardly extending arm of the bell crank lever 38 extends into the bore 4 of one of the ball bearings 3. The bearing 3 rotates freely around the extension 2 and rolls in the cam slot 41, thus oscillating bell cranks 38 which in turn reciprocate the needles 29.

25 As the ball bearings 3 rotate on the extensions 2, the extensions move in and out of the bores 4 at the same time that the balls turn, so that the bores 4 may assume any angle with the vertical necessary to accommodate the angular movement of the levers 38.

30 In operation the strand is drawn down through the knitting head by means not shown. The shaft 21 rotates the needle cylinder 25, its needles 29, and the member 33 with its levers 38. The cams 39 and 40 remain stationary. Thus 35 the depending ends of the levers 38 are carried around rotating the ball-bearings 3 with them and moved in and out by the cam track 41. The horizontal arm of each lever 38 in turn reciprocates a needle 29. The vertical adjustability of the member 33 on the needle cylinder 25 is necessary to vary the length of loops of the knitted fabric. When member 33 is raised or lowered, the bell crank levers 38 move with it and the extensions 2 on the end of the levers slide in and 40 out of the bores 4 of the bearings 3. Thus the

levers 38 are actuated by a ball which has a small amount of friction and yet the vertical adjustability of the bell crank levers is not impaired. In the preferred form of the apparatus shown in this embodiment the cam members 39 and 40 are stationary while the needle carrier 25 rotates. However, the invention would be just as applicable to a machine in which the cam rotates and the needle cylinder is stationary.

The embodiment herein disclosed is illustrative only and may be widely modified and departed from without departing from the spirit and scope of the invention as pointed out in and limited solely by the appended claims.

What is claimed is:

1. In an apparatus for knitting, a plurality of needles, levers to actuate the needles, cam means to reciprocate the levers, and means interposed between the cam means and the levers to cause the cam to reciprocate the levers comprising a ball rotatable and reciprocable on each lever and rolling on the cam means. 20

2. In an apparatus for knitting, a plurality of needles, a lever to actuate each needle, and cam means to reciprocate the levers, said cam means having a lever actuating surface with a curved cross-section, a correspondingly curved member reciprocally and rotatably mounted on each lever and so held by the cam surface as to rotate freely but not reciprocate with respect to the cam, said ball causing the cam means to actuate the levers. 5

10 3. In an apparatus for knitting, a plurality of needles, levers for actuating said needles, and disc-shaped cam means to reciprocate the levers, said cam means comprising two concentric parts forming a cam groove, a cross-section of the groove defining an arc of a circle in each cam part and a ball carried at the end of each lever and operating in said groove, said ball remaining in the same plane in said disc-shaped cam means while moving in said groove.

ROBERT GRANT.
